UNITED STATES PATENT OFFICE.

JOSEPH W. MADISON, OF BROOKLYN, NEW YORK.

MACHINE FOR CAPPING BOTTLES.

SPECIFICATION forming part of Letters Patent No. 738,219, dated September 8, 1903.

Application filed May 9, 1903. Serial No. 156,340. (No model.)

To all whom it may concern:

Be it known that I, JOSEPH W. MADISON, a citizen of the United States, residing at Brooklyn, in the county of Kings and State of New York, have invented certain new and useful Improvements in Machines for Capping Bottles, of which the following is a specification, such as will enable those skilled in the art to which it appertains to make and use the same.

10 The object of this invention is to provide an improved machine for capping bottles with tin-foil or other soft flexible metal after the stopper has been applied; and with this and other objects in view the invention consists 15 in a machine of the class specified constructed as hereinafter described and claimed.

The invention is fully disclosed in the following specification, of which the accompanying drawings form a part, in which the separate parts of my improvement are designated by suitable reference characters in each of the views, and in which—

Figure 1 is a side view of a bottle-capping machine made according to my invention; 25 Fig. 2, a front view thereof; Fig. 3, a vertical section on the line 3 3 of Fig. 2, and Fig. 4 a plan view.

In the practice of my invention I provide a machine of the class specified comprising a base a and two upright frame members a^2 , which are secured to the base and in the top portion of which is mounted a shaft a^3 , provided at one side thereof centrally with a cam-wheel b and centrally with a gear-wheel b^2 . The upright frame members a^2 are also provided at their upper ends with backwardly and upwardly directed arms c , in which is mounted a shaft c^2 , provided at one end with a fly-wheel c^3 and at the other with a fixed 35 pulley c^4 and loose pulley c^5 , and the shaft c is also provided with a gear-wheel c^6 , which is smaller than the gear-wheel b^2 and operates in connection therewith.

Mounted on the base a and in front of the frame members a^2 is a stationary jaw d , which may be formed integrally with the base a , or said jaw may be formed separately and be secured to said base, and said jaw is provided in the top thereof with a rubber bushing d^2 , 45 and over the jaw d is a vertically-movable jaw e , in which is placed a rubber bushing e^2 ,

similar to the corresponding bushing d^2 in the jaw d . The jaw e is provided with a backwardly-directed arm e^3 , which is pivoted to supports e^4 , connected with the base a , as 55 shown at e^5 , and beneath the arm e^3 of the jaw e is a spring e^6 , which normally serves to force said jaw upwardly.

Pivoted to the top of the jaw e at f is a socket member g , in the sides of which are 60 vertically-arranged slots g^2 , through which is passed a pin g^3 , which passes through the lower end of the screw-threaded shank h of a yoke h^2 , and mounted on the shank h of the yoke h^2 is a set-nut h^3 , below which is placed 65 a spring h^4 , which has a bearing h^5 in the top of the socket member g . The opposite sides of the yoke h^2 are provided at their upper ends with vertically-arranged slots or recesses h^6 , which open upwardly and through which 70 the shaft h^3 passes, and the cam-wheel b is secured to the shaft a^3 between the sides of the yoke h^2 , and in the bottom portion of said yoke is a power wheel or roller i , on or in connection with which the cam-wheel b operates. 75

The machine is driven in the usual manner by means of the pulleys c^4 and c^5 , and as the shaft a^3 is turned the cam-wheel b , acting on the wheel or roller i , and the spring e^6 , beneath the jaw e or the arm e^3 thereof, produce 80 a constant vertical movement of the jaw e , and in practice the necks of the bottles to be capped are successively fed into the opening j , between the jaws d and e , in the usual manner. It will be understood that the material 85 with which the necks of the bottles are to be capped is placed thereon in the usual way, and vertical movement of the jaws d and e simply secure the metal around the ends of the necks of the bottles in the usual manner, 90 this operation being accomplished by the vertical movement of the jaw e and the rubber bushings d^2 and e^2 .

In this operation the force of the downward movement of the jaw e is broken to an extent by the spring h^4 , which operates between the set-nut h^3 and the socket member g , this result being accomplished by reason of the fact that the shank h of the yoke h^2 is movable in said socket member, and by reason 95 of this fact the danger of breaking the bottles is largely obviated. The tension of the

spring h^4 may be regulated as desired by the nut h^3 , and the force applied to the jaw e to force it downwardly will be correspondingly regulated, and it will be understood that 5 the spring e^6 operates to raise the jaw e and all the parts connected therewith when the cam-wheel b is not in contact with the wheel or roller i .

Having fully described my invention, what 10 I claim as new, and desire to secure by Letters Patent, is—

1. In a machine of the class described, a frame, a shaft mounted in the top part thereof, a cam-wheel secured to said shaft, a stationary jaw in the bottom of the frame, a vertically-movable jaw operating in connection therewith, a spring for forcing said jaw upwardly, a socket member pivoted to the vertically-movable jaw, a yoke provided with a 15 screw-threaded shank which passes into the socket member, a pin passing through said shank and through vertical slots in the socket member, a set-nut mounted on said shank, a spring placed between the set-nut and the 20 socket member, and a roller mounted in the bottom portion of said yoke and in connection with which the cam-wheel operates, the 25 sides of said yoke being provided with slots

through which said shaft passes, substantially as shown and described. 30

2. In a machine of the class described, a frame, a shaft mounted in the top thereof and provided with a cam-wheel, means for driving said shaft, a stationary jaw in the bottom of said frame, a vertically-movable jaw placed 35 thereover and operating in connection therewith, a spring for raising the vertically-movable jaw, a vertically-arranged yoke in operative connection with the vertically-movable jaw and the sides of which are provided with vertical slots or openings through which said shaft passes, a roller mounted in the bottom portion of said yoke and in connection with which the cam-wheel operates, and means for regulating the force applied to the vertically-movable jaw by the cam-wheel, substantially 40 as shown and described. 45

In testimony that I claim the foregoing as my invention I have signed my name, in presence of the subscribing witnesses, this 7th day 50 of May, 1903.

JOSEPH W. MADISON.
